UNITED STATES PATENT OFFICE.

CALEB WRIGHT, OF PHILADELPHIA, PENNSYLVANIA, ASSIGNOR TO JOSEPH B. ROHRMAN, OF SAME PLACE.

SHEET-METAL-SEAMING MACHINE.

SPECIFICATION forming part of Letters Patent No. 284,584, dated September 4, 1883.

Application filed June 11, 1883. (No model.)

To all whom it may concern:

Be it known that I, CALEB WRIGHT, a citizen of the United States, and a resident of Philadelphia, Pennsylvania, have invented certain Improvements in Sheet-Metal-Seaming Machines, 5 of which the following is a specification.

The object of my invention is to construct a machine for rapidly and effectively double-seaming the joints of sheet-metal cans or boxes 10 of square or other angular shape; and this object I attain in the manner hereinafter set forth, reference being had to the accompanying drawings, in which—

Figures 1, 2, and 3, Sheet 1, are diagrams 15 illustrating the character of the work to be performed by the machine, only those parts of the machine necessary to an explanation of the operations being shown in these views. Fig. 4, Sheet 1, is a longitudinal section. Fig. 20 5 is a detached view, and Figs. 6 and 7, Sheet 2, are respectively a front view and a plan view of an organized machine constructed in accordance with my invention.

In Figs. 1 and 2, *x x* represent the sides of 25 a can, and in Fig. 3 *y* represents the bottom of the same, the shape of the can in the present instance being quadrangular.

Before being subjected to the action of my 30 machine, the corners of the can are united by single-seaming—that is to say, a plain flange on one edge of one side sheet is adapted to a hooked flange on the adjoining edge of the next side sheet, as shown in Fig. 1, the duty of the machine being to bend down these single seams against 35 the sides of the can, so as to form a double seam. The can, having its corners single-seamed, is laid upon the table or bed *A* of the machine, the rear seam of the can bearing against a grooved gage-bar, *B*, on the bed, and the latter being 40 so adjusted that the front seam overhangs the front edge of the table, as shown in Fig. 1, a block, *D*, being then inserted inside the can close against the front side of the same and clamped down, so as to hold the can firmly to 45 the table.

A bar, *F*, is pivoted at its opposite ends to the table *A*, the centers of the pivots being in line with the top and front edges of the table, 50 said bar resting against the front edge of the table when depressed, and having an upper

face flush with the top of the table. This bar *F* has a handle, *a*, and when said handle is drawn up, as shown by the arrow in Fig. 1, the upper face of the bar acts upon the overhanging seam of the can and presses the same up against the side of the can, as shown in Fig. 2. The bar *F* is then depressed, the block *D* removed, and the can readjusted prior to a repetition of the operation in connection with another corner seam. When the bottom or top 60 *y* of the can is to be seamed to the sides, however, as shown in Fig. 3, the block *D* cannot be used; and in this case I use a block, *G*, adapted to rest upon said bottom or top plate, and to fit snugly to the inside of the can, the 65 block being held in place vertically by a rod, *b*, pivoted at the upper end, and adapted to bear upon the block *G* some distance in advance of a vertical line drawn through the pivot, so that the tendency of the rod is to be 70 self-tightening when any backward pressure is exerted upon the block, the rod being free to swing upward when the can is removed from the table. The bottom is single-seamed, as before, and the double-seaming is effected 75 by the bar *F* in the same manner as in forming the corner seams, one side after another being acted upon until the operation is completed.

The manner in which I prefer to construct 80 and operate the various parts above-described is shown in Figs. 4, 5, 6, and 7.

The gage-bar *B* slides on the top of the table *A*, and is confined vertically and laterally thereto by bolts *d* and nuts *d'*, the heads of the 85 bolts being adapted to and free to slide in longitudinal *L*-shaped grooves *e* in the bed. The adjustment of the gage-bar is effected by set-screws *f*, which are adapted to threaded lugs *f'* on the rear edge of the table, the points of 90 the screws bearing against the rear edge of the gage, and said screws thus serving not only to adjust the bar, but also to resist the thrust exerted upon the same when the bar *F* is bending the front seam. The gage-bar *B* is of a 95 length equal to the width of the largest can to be seamed upon the machine, so that it will bear throughout upon that edge of the sheet opposite to the edge which is being acted upon by the bending-bar, and in order to effectually 100

resist the strain exerted upon the bar the bolts *d* and set-screws *f* are arranged near each end of the latter.

The clamp-block *D* rests at each end upon a spring, *g*, and is acted upon by cam-levers *H*, hung to brackets *h* on the table *A*, and connected by rods *i* to a suitably-located treadle, springs *i'* serving to retract the levers when pressure is removed from the treadle. The block *D* is loose and disconnected from the table *A* or levers *H*, in order that it may be readily removed when all four edges of the can have been seamed.

The bending-bar *F* is hung to lugs *m* on the bed, and the acting edge *n* of said bar is beveled in opposite directions from the center to each end, as shown in Fig. 6, and from edge to edge, as shown in Fig. 4, the object of thus beveling the bar being to distribute the strain on the same during the bending operation, and to compensate for the springing of the metal of the can under the action of the bar, and being secured by a set-screw, *t*.

The retaining-rod *b* is secured by set-screws to a bar, *p*, pivoted at the ends to standards *P* on the table, the rod being adjustable in respect to the bar, so as to bear properly upon blocks of different thicknesses, and the posts being adjustable longitudinally, as shown in Fig. 5, as may be demanded by cans of different sizes, the posts being secured in position after adjustment by bolts *v*, adapted to slots *v'* in the posts.

The table *A*, clamp-block *D*, and bending-bar *F* are all slotted for the reception of the ribs or flanges with which the sides of cans are sometimes provided.

Instead of employing a self-tightening rod, *b*, for the purpose of retaining the block *G*, a

rod acted upon by cams or by a screw carried by the bar *p* may be employed, the device shown being preferred, however, as the simplest.

I claim as my invention—

1. The combination of the table *A* and the pivoted bending-bar *F* with the disconnected clamping-block *D* and with means for depressing the same, as set forth.

2. The combination of the table *A*, the bending-bar, and the clamping-block with the gage-bar *B*, constructed to bear throughout upon that edge of the sheet opposite to the edge which is being bent, and combined near each end with a clamping-bolt, *d*, and a set-screw, *f*, the latter being adapted to lugs on the table and bearing on the rear edge of the bar, as set forth.

3. The combination of the table *A* and clamping-block with a pivoted bending-bar, *F*, the acting face of which is beveled in opposite directions from the center to each end, as set forth.

4. The combination of the table *A*, the pivoted bending-bar *F*, and the clamping-block *G* with the pivoted retaining-rod *b*, as set forth.

5. The combination of the table *A*, the pivoted bending-bar *F*, the block *G*, the adjustable posts *P*, the bar *p*, pivoted thereto, and the retaining-rod *b*, adjustable in said bar *p*, as set forth.

In testimony whereof I have signed my name to this specification in the presence of two subscribing witnesses.

CALEB WRIGHT.
